SIGN LETTER

Samuel G. Lang, 3rd, Cincinnati, Ohio, assignor
to W. A. Barrows Porcelain Enamel Company,
Cincinnati, Ohio, a corporation of Ohio

Application July 15, 1937, Serial No. 153,798

9 Claims. (Cl. 40—140)

The present invention relates to the fabrication of sheet metal shapes in such a manner as to enhance and facilitate the application of baked or fired finishes.

5 Another object of the invention is to improve the quality, appearance, and durability of articles fabricated of sheet metal and coated or decorated with baked or fired finishes.

10 A further object of the invention is the production of articles of the character stated, by means of a simple, inexpensive, and effective method or procedure whereby perfection in the finished product is assured, and special final retouching or corrective operations are effectively eliminated.

15 More specifically, it is an object of the present invention to provide a novel method and means of forming sheet metal block letters, allowing great latitudes in all dimensions of the letters, and enabling the production of such letters in 20 any sizes and with their faces set at various depths relative to their sides, without resort to special manufacturing operations.

The foregoing and other objects are attained by the means described herein and disclosed in 25 the accompanying drawing, in which:

Fig. 1 is a perspective view of a block letter embodying the invention.

Fig. 2 is a fragmental perspective view showing 30 one end of a block letter, this being a modification of the Fig. 1 construction.

Fig. 3 is a view of the Fig. 2 construction inverted to show the back thereof.

Fig. 4 is a fragmental perspective view showing 35 a further modification of block letter construction.

35 For convenience of illustration and explanation of the invention, the fabrication of sheet metal block letters will be treated throughout the specifications, with the understanding, however, that the invention is applicable to other structures or 40 shapes which generally are coated with a finishing substance, particularly porcelain enamel, or other vitreous or siliceous compositions applied by means of a baking or firing process.

In the past, the baking or firing of coated sheet 45 metal letters or other built-up objects constructed basically of sheet metal, was attended by several serious and vexatious difficulties that resulted in poor finishing, warping, and other imperfections which rendered the manufacture of such 50 articles costly as well as unsatisfactory of results. The practice had been to construct or build up the letters or articles by fitting sheet metal sections together, and making a composite structure by means of a continuous gas weld, or line welds 55 connecting adjacent sections. The prior prac-

tice required no particular kind of joint between the sheet metal sections, other than one that would be sufficiently strong, and convenient to form. Such joints being more or less common, they were employed indiscriminately in forming 5 the different parts of the letters or other shapes. The result of all this was the unsatisfactory fabrication of shapes that would buckle or warp during the welding process, and under application of the baking or firing heat of 1300 to 1600 10 degrees. Also, difficulty was experienced in causing the coating, (particularly porcelain enamel), to adhere to the weld because of the composition of the flux used, or possibly due to oxidation or chemical changes in the metal resulting in effect- 15 ing a gas weld. Another objection to the old practice was the formation of shapes having exposed raw metal edges which, due to their sharp and thin character, failed to hold the coating material in sufficient quantity to obviate the tendency toward transparency of the coating at said 20 edges. On numerous occasions, the coating would completely leave the raw edges during the baking or firing process, and a very poor and unsatisfactory job would result. All of these 25 objectionable features of the prior practice, as well as some minor ones, have been obviated by means of the present invention which will now be described in detail.

With reference now to the accompanying draw- 30 ing, the character A indicates a block letter or other shape having a face properly cut from sheet metal to establish a desired contour or design. This face piece has no flanges, and it may accordingly be formed quickly and accurately 35 with a minimum of effort and time expenditure.

The face piece 5 is bounded by side pieces which, if made in separate sections, may be identified by the characters 6, 7, 8, 9, and 10. The sections 6, 7 and 8, may be made up of a single strip prop- 40 erly bent to follow a continuous edge of the face piece, if desired, and such practice may apply also to the sections 9 and 10.

Each side piece or section comprises a body or 45 main portion and an integral inwardly and down- wardly turned flange 12 formed along the upper or outer edges 13 thereof, said flanges providing abutments for the edges 14 of the face piece 5. To these flanges or abutments 12, the face piece may be welded electrically at intervals along the 50 face piece edges, interiorly of the shape or letter, as indicated most clearly at 15 in Figs. 1 and 3. The welds preferably connect the face piece to the flanges 12 and to the main body portions of the side pieces, (see Fig. 3), thereby to produce flex- 55

ing or separation of the flanges from the body portions of the side pieces. The positioning and the welding of the parts may be performed in a suitable jig, (not shown), if desired.

- 5 At this point, it may be noted that all the exposed edges 13 are rounded, and they present smoothly finished surfaces of sufficient area to hold a desired thickness of porcelain enamel or other coating material to be baked on or fired.
- 10 Of equal importance is the fact that the present construction permits of setting the face of the letter deeply beyond the edges 13, as in Fig. 2, or close to the edges as indicated by Fig. 1. When the face is to be deep-set, as in Figs. 2, 3, and 4, it is necessary only to increase the width of flanges 12 to a desired extent, and set the face piece in position for welding as heretofore described. This may be desirable in the application of gaseous tube illumination for the letter or shape, as indicated by the character 16 of Fig. 4.

The drawing illustrates several modes of mounting the letters or shapes upon a wall or other support. In Fig. 1 is shown a mounting stud 17 welded or otherwise suitably fixed to a flange or edge 18 interiorly of the shape, this stud being threaded for reception of a nut. It will be understood, of course, that the shape may carry a plurality of mounting studs 17. In Figs. 2 and 3, the mounting means is a screw or bolt 19 having an extending threaded end, and a head 20 welded or otherwise fixed to the back of the face piece 5.

Fig. 4 discloses a mounting means in the form of a base plate 21 having one or more key-hole slots 22 formed therein whereby the shape may be hung upon the heads of screws, nails, studs or the like fixed to a supporting surface. The base plate may be welded or otherwise fixed to the side pieces 6 and 8, there being shown supporting flanges 23 and 24, and welds 15, for the purpose. It should be noted that in each form of the device of the invention, the raw edges of the face pieces 5 have a line abutting relationship 45 with the surfaces of flanges such as 12 near the free edges of the flanges, where the welds may be applied at intervals or possibly continuously along said edges. As before stated, this construction eliminates strains in the metal and obviates the buckling and warping which previously was a fault causing considerable difficulty and expense in the manufacture of articles such as those under consideration. The construction herein disclosed insures production of a uniformly thick coating on all exposed edges of the letter or shape, and presents an indication of superior workmanship in the manufacturing process. Objects made in accordance with the present invention have been found highly acceptable due to their sturdy construction and the ability to withstand abuse and careless handling. Other advantages have been stated earlier in the specifications.

It has been found advantageous to employ in the process of this invention, that form of welding known as tack welding, using an electric arc, although it is conceivable that spot welding or line welding either by gas or electricity may be employed under proper conditions, or possibly 70 with the loss of one or more but not all of the advantages specified herein. In the tack welding process, welding metal in small amounts is added to the surfaces joined, whereas spot welding generally is effected without the addition of metal.

It is to be understood that various modifications and changes may be made in the structural details of the device, within the scope of the appended claims, without departing from the spirit of the invention.

5

What is claimed is:

1. The method of manufacturing shapes to be individually mounted upon a support, which method comprises the forming of a sheet metal face piece of a desired contour, and of side pieces 10 having edges turned upon themselves to form interior flanges upon the body portions of the side pieces, placing the raw edges of the face piece in edgewise abutment upon the faces of the flanges, and tack-welding the edges of the 15 face piece to the faces of the flanges, and thereafter applying a vitreous coating by baking or firing, to the resultant joint.

2. The method of manufacturing sheet metal shapes to be subjected to coating and baking, said 20 method comprising the forming of a sheet metal face piece of a desired contour, and of side pieces each having a body portion with a flange along an edge thereof, placing the face piece between a plurality of such side pieces with the edges of 25 the face piece abutting the flanges substantially at right angles, then electrically tack-welding the face piece edges to the flanges at intervals along their length, to avoid setting up molecular strains which tend to distort the shape and de- 30 tract from its appearance and ease of mounting, and thereafter coating the face piece and side pieces with porcelain enamel and subjecting the entire structure to a baking process whereby to provide a continuous porcelain seal at and adja- 35 cent to the joints formed by abutting the edges of the face piece with the flanges of the side pieces.

3. In a structure of the class described, the combination of a face piece having opposed raw 40 edges, and means in the form of side walls for confining and bounding said raw edges, the side walls each having a flange along an edge thereof turned inwardly and substantially flatly against the side wall, the terminal edge of the flange 45 being extended along the side wall with a predetermined extent of overlap depending upon the depth at which the face piece is to be inset within the confining side walls, means securing the face piece edges at intervals to an adjacent face of 50 the flange and a continuous vitreous coating extending over said face piece and side walls and sealing the joint formed by the abutting portions of said face piece and side walls.

4. In a structure of the class described, the 55 combination of a face piece having opposed raw edges, and means in the form of side walls for confining and bounding said raw edges, the side walls each having a flange along an edge thereof turned inwardly and substantially flatly against 60 the side wall, the terminal edge of the flange being extended along the side wall with a predetermined extent of overlap depending upon the depth at which the face piece is to be inset with the confining side walls, means securing the face 65 piece edges at intervals to an adjacent face of the flange, a continuous vitreous coating extending over said face piece and side walls and sealing the joint formed by the abutting portions of said face piece and side walls, and means for 70 mounting the structure upon a support.

5. As a new article of manufacture, a block 75 letter comprising a pair of side walls arranged in spaced relationship, inwardly turned flanges along corresponding edges of said side walls, the

flanges extending downwardly between the walls and against their respective side walls, mounting studs fixed to and extending from the side walls in the general direction of flange extension, a 5 face piece fitted between the walls to abut the flanges thereof edgewise, a series of spaced tack welds joining the flange-contacting edges of the face piece to the edges of the flanges and to the inner faces of the side walls and a continuous 10 vitreous coating extending over said face piece and side walls and sealing the joint formed by the abutting portions of said face piece and side walls.

6. A device of the class described comprising 15 in combination a face sheet having a raw edge, and a bounding member in the form of a wall, said bounding member having a body portion with a wide flange turned upon the body portion to form a rounded smooth edge at the line of 20 turning, leaving a free edge of the flange lying close to the body portion but at a distance from said line of turning, a weld joining the raw edge of the sheet in edge-butting relationship to a face of the flange, at substantially the location of 25 the free edge line of the flange and a continuous vitreous coating extending over the rounded smooth edge of the bounding member and over the joint formed between said flange and said raw edge of the sheet.

30 7. A device of the class described comprising in combination a face sheet having a raw edge, and a bounding member in the form of a wall, said bounding member having a body portion with a wide flange turned upon the body portion 35 to form a rounded smooth edge at the line of turning, leaving a free edge of the flange lying close to the body portion but at a distance from said line of turning, a weld joining the raw edge of the sheet in edge-butting relationship to a face 40 of the flange, at substantially the location of the

free edge line of the flange, and to the body portion of the bounding member adjacent to said free edge line and a continuous vitreous coating extending over the rounded smooth edge of the bounding member and over the joint formed between said flange and said raw edge of the sheet. 5

8. The method of manufacturing shaped characters to be unified in a composite sign or the like and which method comprises forming a sheet metal face piece member of a desired shape or 10 contour with an unfinished lateral or peripheral edge, forming a side piece member conforming to the shape of said face piece member and having a downturned lateral flange, placing the lateral edge of the face piece member in abutment 15 against the lateral flange of the side piece member and permanently securing together the said contacting portions of the side piece member and the face piece member, and thereafter applying a vitreous coating to said face and side piece 20 members and the joint therebetween by baking or firing, whereby the vitreous coating seals and provides a continuous vitreous surface over said joint between said members. 25

9. In a device of the class described the combination of a sheet metal face piece member of a desired shape or contour having an unfinished lateral or peripheral edge, a sheet metal side piece member conforming to the shape of said face piece member and comprising a body portion and an integral downturned flange disposed adjacent to and in substantial parallelism with the body portion thereof, the flange having fixed contact and connection with the peripheral edge of the face piece member, and a continuous coating 30 of vitreous material extending over and sealing the joint between the face piece and the side piece members. 35

SAMUEL G. LANG, 3RD. 40
